UNITED STATES PATENT OFFICE.

JOSEPH B. INGALLS, OF CHICAGO, ILLINOIS.

COIN BANK.

Application filed February 23, 1923. Serial No. 620,819.

This invention relates to registering coin banks and has for its primary object the provision of means whereby unlocking of the bank before the predetermined number 5 of coins has been inserted will be prevented. The invention also seeks to provide a mechanism which will be inoperative until a coin has been inserted and will then require the application of pressure by the user of the 10 bank in order to effect passage of the coin into the coin receptacle or chamber and also cause the coin to actuate the counting devices. These stated objects, and other objects which will incidentally appear, are attained in the use of such a device as is illustrated in the accompanying drawings, and the invention resides in certain novel features which will be particularly pointed out 15 in the appended claims.

20 In the drawings:

Figure 1 is a perspective view of my improved coin bank;

Fig. 2 is a view, partly in section and partly in elevation, of the bank with the 25 cover or face plate removed;

Fig. 3 is a view similar to Fig. 2 of the upper portion of the bank showing the operating mechanism in a position different from that shown in Fig. 2;

30 Fig. 4 is a similar view with the partition and part of the operating mechanism removed;

Figs. 5, 6 and 7 are perspective views of different members of the casing.

35 Fig. 8 is a detail section on the line 8—8 of Fig. 1.

In carrying out my invention, I employ an outer or back casing member consisting of a plate 1 having a flange or rim 2 across one 40 end and side rims 3 along its sides extending from the rim 2, the end of the plate opposite the end having the rim 2 being free of all rims or projections and all the rims being constructed with overhanging inwardly projecting flanges 4. This member of the casing 45 may be stamped from sheet metal of proper gage and will obviously be capable of very economical and rapid production. In the rim 2 are formed slots 5 and 6 for a purpose

50 which will presently appear and at any convenient point in the back plate 1 is a threaded opening 7. The casing also includes an intermediate member shown in Fig. 6 and comprising a back plate 8 having an opening 9' therethrough adapted to register with the opening 7 in the plate 1, and rims or walls 9

rise from the side edges of this plate but terminate short of the lower end thereof, the said walls or rims 9 being connected by a transverse rim or wall 10 at one end of the 60 plate, which rim or wall 10 is constructed with slots 11 and 12 adapted to register with the slots 5 and 6, as will presently appear. A front plate 13 is secured upon the edges of the rims or walls 9 and 10 by suitable screws, 65 indicated at 14, inserted through the said front plate and engaging bosses on the plate 8 in a well-known manner. The front plate 13 is provided with openings 15 to receive the ends of the hubs or shafts of counting 70 wheels, and sight openings 16 are also formed in the said front plate to permit reading of the indicators upon the counting wheels. The front plate is given an irregular outline which will correspond to the form of a partition 17 presently more particularly referred to so that below the said partition a chamber for the reception of the deposited coins will be provided and above the said partition a closed chamber will be provided 75 in which the operating mechanism will be housed. The cover or face plate 18 is a flat plate of rectangular outline and of the same area as the intermediate member of the casing and said plate 18 is adapted to extend over the said intermediate member so as to 80 cover the entire front of the same. The said face plate 18 is provided at its lower end with a rim 19 upon which is an external knob or projection 20 to facilitate the removal of 85 the cover when the bank has been filled, and at the sides of the said face plate are flanges or rim members 21 which are adapted to abut the lower ends of the rims 9 of the intermediate member of the casing so as to lie 90 flush therewith and, in effect, form continuations of the same. The rim or flange member 21 which lies against the extended portion 22 of the face plate 13 is provided with an opening 23 therein which is adapted to be 95 engaged by the lower end of a latch or locking lever 25 housed within the intermediate member of the casing and adapted to be actuated by the counting devices. In actual practice, the counting wheels, one of which 100 is shown at 26, are provided with elements adapted to act upon the latch 25 whereby, when the first coin is inserted, the latch will be moved into locking position and when the last coin of the predetermined number is 105 inserted the latch will be actuated to be withdrawn from the locking position and the 110

cover member 18 may then be withdrawn from the casing so that the coins may be removed. The actuation of the latch by the counting devices in the manner described forms no part of my present invention and the arrangement by which it is effected has not, therefore, been illustrated. It may sometimes be desired to require the banks to be brought to a certain bank or other place of deposit in order to be opened and in order that it may be used for this purpose the latch will be free of the counting or registering devices and will be released by a key maintained in the custody of some one at the central place of deposit. To permit such use of the device, keyholes 27 will be provided in the back plate and the intermediate member of the casing, as indicated, and the key, indicated at 29, will, of course, be kept by the custodian.

Intermediate the back plate 8 and the front plate 13 of the intermediate member of the casing and parallel therewith, a partition 30 is secured within the said member in any convenient or preferred manner. The upper portion of the partition 17 terminates at the lower portion of the recesses or chambers thus provided and the said partition 30 terminates adjacent but in spaced relation to the counting wheels which are indicated at 26. When the parts of the casing are assembled, the slots 5 and 11 are caused to register, as shown clearly in Fig. 4, and together form an entrance for the coin, indicated at 31, a guide block 32 being secured between the partition 30 and the back plate 8 so as to prevent the coin rolling against the counting devices and to direct it downwardly into engagement with the actuating elements and eventually into the coin chamber in the lower portion of the casing. Pivotedly mounted between the back plate 8 and the partition 30 below the guide block 32 is a dog 33 having one end normally projecting into the path of the inserted coin to be inserted and its other end normally resting against a stop 34, as shown clearly in Fig. 4. The pivot of this dog 33 extends through the partition 30 and has secured upon its front end a trip 35 having a lug 36 disposed above the pivot and engaged by a spring 37 secured upon the partition 30 whereby the said trip will be normally held in the position shown in Fig. 2. This trip has a curved finger 38 extending downwardly and then inwardly so that it will be in the same plane as the counting wheel 26 and may actuate said wheel. The trip is further provided with a locking lug 39 projecting in a direction away from the counting wheel and normally overhanging and resting on a stop lever 40 which is pivotally mounted upon the partition 30 and normally extends upwardly from its pivot so as to engage the free end of the lug 39 and then extends

toward the adjacent side of the casing, its free end being provided with a stud or projection 41 which is adapted to be engaged by an inserted coin which will thereupon actuate this stop lever so that it will be swung out of engagement with the lug 39 of the trip 35 to permit said trip to swing so as to actuate the counting wheel. The stud 41 plays in an opening 42 provided therefor in the partition 30, and a spring 43 is secured upon the partition and bears against the lever so as to yieldably hold it in its normal position, as will be readily understood upon reference to Fig. 2. Pivotedly mounted between the partition 30 and the back plate 8, at a point below the coin entrance slots and between the ends of said slots and the adjacent side of the casing, is a pusher 44 which is adapted to bear upon an inserted coin when properly actuated so as to force the coin downwardly within the casing against the stud 41 and the projecting end of the dog 33. The pusher, as clearly shown in Fig. 4, is pivoted at its lower end, and between its ends is provided with a forwardly projecting pin or stud 45 playing in an arcuate slot 46 in the partition 30 concentric with the pivot of the pusher. A plunger 47 is slidably mounted between the partition 30 and the face plate 18 and against the adjacent side of the casing and projects through the slots 12 and 6, as will be readily understood upon reference to Figs. 1, 2 and 3. The plunger 47 is provided with a head or finger piece 48 which is detachably mounted thereon and is secured thereto after the parts have been assembled thereby facilitating the fitting of the parts together and also constituting a stop to limit the inward movement of the plunger by reason of its contact with the end of the casing. The plunger is held to a rectilinear path by any convenient guiding devices within the casing, indicated at 49, and a spring 50 is mounted upon the partition 30 or other fixed part and bears against the inner end of the plunger so as to yieldably hold it in its outermost position. The plunger is provided with a cam slot 51 which engages the front projecting end of the stud 45 so that, if the plunger be pushed inwardly, the pusher 44 will be swung pivotally, as will be readily understood.

It will now be understood that, when a coin is inserted, it will come to rest below the slots 5 and 11 upon the projecting end of the dog 33 and upon the stud 41 of the stop lever 40, these parts being located at such a distance below the entrance slots that further pressure by the finger cannot be exerted upon the coin and the progress of the coin will be arrested until the stop lever has been actuated. To accomplish this result, the plunger 47 is pressed inwardly and the pusher 44 is thereby swung over and against

the coin, indicated at 31, and will press the same downwardly, it being noted at this point that the stud 41 is slightly above the inner end of the dog 33 when the parts are at rest. Consequently, the coin will press upon the stud 41 and push the same laterally so that the stop lever 40 will be swung to the position shown in Fig. 3, and moved from below the stop lug 39 of the trip 35. 5

10 Simultaneously with the movement of the stop lever from below the lug 39, the coin will actuate the dog 33 so as to rock the same and as the trip 35 follows the movement of said dog, the finger 38 of the trip will be 15 swung against one of the projecting points or teeth of the counting wheel 26 and the said wheel will be rotated one step. The pressure of the plunger is continued until the coin clears the dog 33, whereupon the spring 20 37 will return the dog and the trip to their initial positions. The pressure upon the plunger being then relieved, the springs 43 and 50 will return the stop lever and the plunger to their respective initial positions 25 and the return movement of the plunger will, of course, carry the pusher 44 back to its normal position so that the parts will be disposed to receive another coin. It will be readily noted, upon reference to Figs. 2 and 30 3, that the slot or notch 51 is defined by two lateral curved fingers projecting from an edge of the plunger, and the upper finger 52 will bear upon the trip 35, when the plunger is depressed, and thereby aid in turning the trip and cause it to positively actuate the counting wheel. The release of the coin is 35 also made positive and certain.

It will be readily noted that my device is simple and compact and easily operated. In 40 devices heretofore produced, it was possible to open the bank before the predetermined number of coins had been inserted inasmuch as a pin, knife blade, or other implement could be inserted through the coin entrance slots and pressure exerted upon the member corresponding to the dog 33 to actuate the counting wheel step by step until the latch 45 25 was released. In the mechanism herein disclosed, such manipulation is not possible inasmuch as the trip 35 is not accessible from the outside of the casing and being fast with the dog 33 it will resist movement of the dog until the stop lever 40 has been shifted out of engagement with the stop lug 39 of the trip. The stop lever cannot be so 50 shifted until a coin has been inserted inasmuch as the stud 41 on the stop lever cannot be reached by a wire or other implement and is not engaged at any time by the plunger so 55 that pressure exerted upon the plunger will be unavailing unless a coin has been inserted. Should a wire or other implement be inserted so as to engage the stud 41, it would 60 extend across the path of the pusher 44 and block the movement of the same so that the lock could not be picked. When the latch has been released, the coins are removed by merely pulling the outer or front member of the casing from its position over the intermediate member of the casing, whereupon 65 the open end of the casing will be exposed and the coins may drop out. The trim members 2 and 3 of the back member or outer member of the casing are of such height that the intermediate and front members of the casing will be snugly received therein and will be held frictionally thereby, the fit being such that, while the intermediate and front members of the casing may be easily inserted without binding, the engagement will 70 be sufficiently tight to prevent accidental withdrawal unless the latch be released, and a single screw, indicated at 60, inserted through the back plate of the intermediate member of the casing into the back plate 1 75 will securely hold the parts together. 80

Having thus described the invention, what is claimed as new is:

1. In a coin bank, the combination of a counting mechanism, a trip at one side of the path of an inserted coin for actuating said mechanism, means extending into the path of an inserted coin for operating the trip, means extending into the path of the coin for holding said trip normally inoperative, 90 a pusher adapted to engage an inserted coin, and means for operating said pusher whereby the coin will be caused to release the stop device and actuate the trip whereby to operate the counting mechanism. 95
2. In a coin bank, the combination of a counting mechanism, a trip to be actuated by an inserted coin and operate the counting mechanism, a stop member to be actuated by an inserted coin normally holding 100 the trip in inoperative position, a pusher, and means for operating the pusher whereby to force an inserted coin into engagement with the stop device and release the same and then actuate the trip, said means including an element to engage the trip and assist the coin in actuating the same. 110
3. In a coin bank, the combination of a counting mechanism, a trip for operating the counting mechanism, means whereby said trip may be actuated by an inserted coin, a stop lever normally engaging the trip and holding it in an inoperative position, said stop lever having an element interposed in the path of an inserted coin, a pusher adapted to engage an inserted coin, and a plunger having operative engagement with said pusher whereby to cause the coin to first release the stop lever and then actuate the trip. 115
4. In a coin bank, the combination of a pusher disposed at one side of the path of an inserted coin, a stud on the side of said pusher, a plunger slidably mounted adjacent the pusher and provided with a cam slot 120 125 130

engaging the said stud, a trip to be actuated by the coin, and a stop lever normally holding said trip inoperative and having an element projecting into the path of the coin whereby when the coin is moved by the pusher the stop lever will be released and the trip actuated.

5. In a coin bank, the combination of a trip to be actuated by an inserted coin, a 10 stop lever mounted adjacent the trip and normally engaging the same to hold it in inoperative position, a stud projecting laterally from the free end of the stop lever into the path of a coin, a plunger, a finger 15 projecting laterally from the plunger to engage the trip, and means operated by the plunger for moving the coin past the stop lever and the trip whereby the stop lever

will be moved out of engagement with the trip and the trip then actuated.

6. In a coin bank, the combination of a 20 dog having a portion projecting into the path of an inserted coin, a trip fast with said dog and having a finger adapted to actuate a counting device, and a stop lug 25 on the trip projecting normally inwardly, a stop lever arranged adjacent the trip and normally engaging the stop lug to prevent movement of the trip, said stop lever having an element projecting into the path of the 30 inserted coin to be engaged thereby in advance of the engagement of the dog by the coin, and means for moving the coin past said element and the dog.

In testimony whereof I affix my signature.
JOSEPH B. INGALLS. [L.S.]
